ORNAMENTAL RAILING

Louis Blum and William J. Horgan, Jr., Pittsburgh, Pa.,
assignors to Blumcraft of Pittsburgh, Pittsburgh, Pa.,
a firm

Original design application July 28, 1965, Ser. No. 86,318.
Divided and this application Dec. 15, 1966, Ser. No.
5,974

Term of patent 14 years

(Cl. D13—7)

FIG. 1.

FIG. 2.

FIG. 4.

FIG. 1 is a perspective view of an ornamental railing embodying our new design wherein the shading on the panels represents glass;

FIG. 2 is a view along the lines II—II of FIG. 1;

FIG. 3 is a view along the lines III—III of FIG. 1; and

FIG. 4 is a view of another railing embodying our new design, wherein the shading on the panels represents glass.

The characteristic and essential features of the design reside in the portions shown in full lines.

The steps and wall shown in broken lines are disclosed for illustrative purposes only.

We claim:

The ornamental design for an ornamental railing, as shown and described.
